United States Patent Office

Des. 193,558
Patented Sept. 11, 1962

193,558

BIRD FEEDER

Robert D. Parry, 1336 Custer Ave., Cincinnati, Ohio

Filed Feb. 1, 1961, Ser. No. 63,788

Term of patent 14 years

(Cl. D31—2)

FIGURE 1 is a bottom perspective view of a bird feeder embodying my new design.

FIGURE 2 is a side elevational view thereof.

FIGURE 3 is a top plan view thereof.

FIGURE 4 is a cross sectional view taken on the line 4—4 of FIGURE 2.

I claim:

The ornamental design for a bird feeder, substantially as shown.
